UNITED STATES PATENT OFFICE.

LLEWELLYN GERMAN, OF ALLENSTOWN, PENNSYLVANIA.

THILL-COUPING.

SPECIFICATION forming part of Letters Patent No. 341,744, dated May 11, 1886.

Application filed March 26, 1886. Serial No. 196,631. (No model.)

To all whom it may concern:

Be it known that I, LLEWELLYN GERMAN, a citizen of the United States, residing at Allentown, in the county of Lehigh and State of Pennsylvania, have invented new and useful Improvements in Thill-Couplings, of which the following is a full and exact description, reference being had to the accompanying drawings, making part of this specification.

10 My invention relates to improvements in thill-couplings, and has for its objects to provide a safe, solid, and simple construction; a construction adaptable to different sizes of thill-bolts without dismemberment or waste 15 of time; and a construction which prevents any rattling in the coupling caused by wear.

Figure 1 is a side view of my invention. Fig. 2 is a longitudinal section of the same. Fig. 3 is a plan view of the under side. Fig. 4 is a 20 side view showing the parts in position before coupling.

Thill-couplings have heretofore been subject to many difficulties and inconveniences. The constructions have many separate parts, 25 which are apt to become detached and lost, and require careful adjustment, or they are large and unsightly. These difficulties and inconveniences are obviated by the construction shown in the accompanying drawings, 30 in which A is a thill-iron, provided with a perforation for a short bolt, E, and having at its rear end a hook, forming at its inner angle a bearing for the thill-bolt, and widening as it opens with straight sides. The leg A' 35 of this hook reaches back and below the body A of the thill-iron, and is coupled by a hinge to a flexible spring-band, a. Through the perforation in the thill-iron A, before spoken of, is passed a threaded bolt, E, which engages 40 an elongated nut, B, and draws it close to the thill-iron A. This elongated nut B is provided at its forward end with a loose thumb-screw, C, the head of which is countersunk in B, so as not to prevent the close contact between A and B, and at its rear end it is 45 attached by a hinge-joint to the swinging part b. This swinging part b is of the same thickness as B until it reaches the shoulder of the thill-iron A, forming the hook or bearing for

the thill-bolt f, when it is enlarged to conform 50 to the hook, as shown in Figs. 2 and 4, and forming the under side of the bearing for bolt f. The bolt shown in drawings is of the smallest size, and the parts are all close together; but in practice this is not the case, there always being a little play. The flexible spring-band a passes over this swing part b and engages the thumb-screw C by means of a narrow slot, a', cut in it for that purpose.

The operation of my invention is as follows: 60 When it is desired to couple, the parts are placed in the position shown in Fig. 4, when the spring a and hook A' are passed over the thill-bolt f. The swinging portion is then put in place and the spring-band a made to engage 65 the thumb-screw C, which is turned crosswise of the slot a', and all the parts are securely locked in position. If the bolt f is large, the parts are held slightly apart, but with no danger of rattling, as the spring-band a presses 70 the bearing b' firmly against the bolt. When it is desired to uncouple, the thumb-screw is turned until the spring-band is released, when the parts assume the position shown in Fig. 4.

What I claim is—

1. In a thill-coupling, the combination of a thill-iron forming at one end a hook-bearing, with an adjustable bearing conforming with said hook and hinged to said thill-iron, and a flexible spring operating upon said adjustable bearing, substantially as set forth.

2. In a thill-coupling, the combination of a thill-iron forming at one end a hook-bearing, with an adjustable bearing conforming with said hook, an elongated nut attached to said 85 adjustable bearing and to said thill-iron, a flexible spring-band attached to said thill-bearing and provided with an elongated slot, and a thumb-screw attached to said thill-iron and placed so as to engage said flexible spring-band, substantially as set forth.

In testimony whereof I have hereunto set my hand this 22d day of March, A. D. 1886.

LLEWELLYN GERMAN.
